ASH TRAY

Elvin Schwartz, R.D. 1, Union City, Pa.

Filed Dec. 23, 1960, Ser. No. 63,315

Term of patent 14 years

(Cl. D85—2)

FIG. 2

I claim:

The ornamental design for an ash tray, as shown.
